UNITED STATES PATENT OFFICE.

ANDREW SEKULA, OF WASHINGTON, PENNSYLVANIA.

UTENSIL-LIFTER.

1,176,173.

Specification of Letters Patent. Patented Mar. 21, 1916.

Application filed February 23, 1915. Serial No. 9,967.

To all whom it may concern:

Be it known that I, ANDREW SEKULA, a subject of the Emperor of Austria-Hungary, residing at Washington, in the county of 5 Washington and State of Pennsylvania, have invented certain new and useful Improvements in Utensil-Lifters, of which the following is a specification.

This invention relates to certain new and 10 useful improvements in utensil lifters.

The present invention aims to provide a utensil lifter that may be readily attached to the handle of a utensil or projecting strap and be locked thereto so that the same will 15 not become accidentally disengaged.

The present device is simple in construction and inexpensive to manufacture and constitutes a useful article, the same being preferably constructed of thin sheet metal 20 with the lifting end thereof made resilient and having associated with the resilient end a locking rod.

The invention will be hereinafter described in detail, and reference will be had 25 to the accompanying drawing by like characters designating corresponding parts throughout the several views, and wherein:

Figure 1 is a side elevational view of the lifter attached to a portion of a utensil, 30 with the utensil and lifting end of the device in section. Fig. 2 is a side elevational view of the same. Fig. 3 is a top plan view showing the same locked to a strap on a utensil. Fig. 4 is a top plan 35 view of the same, with the locking rod turned to disengaging position, and, Fig. 5 is a detail perspective view of the lifting end of the device.

Referring more in detail to the accompanying drawing, the reference numeral 10 40 designates a portion of a vessel of any suitable construction, which vessel carries the bowed strap 11 adapted to be engaged by the lifter 12.

The lifter is preferably formed of thin sheet metal and includes the handle portion 13 having the rounded side edges 14 while the lifting end thereof is bent to substantially U-shape and includes a pair of side walls 15 and 16 connected by the integral bottom wall 17.

The spaced walls 15 and 16 are made resilient and while not in use, assume the distended position shown in Fig. 2, the projection of the side wall 16 being further held 55 in such position by the spring 18. This

spring includes the right-angularly bent lower end 19 which is of a width substantially equal to the distance between the walls 15 and 16 when the same are parallel, 60 to thereby limit the movement of the side walls toward each other. An eyelet 20 projects centrally from the upper end of the spring 18 and extends through an opening 21 provided adjacent the upper end of the 65 wall 15 while the inner projecting end thereof is swaged as at 22 to hold the same in position on the wall.

The locking means associated with the lifter 12 is carried by the handle portion 13, 70 there being provided lugs 23 carried by the bottom wall of the handle, and through which lugs projects the locking rod 24. The forward end of the rod projects through the eyelet 20 and has the projecting end thereof 75 bent to provide a finger 25 normally positioned between the side walls 15 and 16, but in locked position with respect to the lifting end of the lifter, the finger is adapted to be received in the recessed portion 26 formed 80 in the outer upper edge of the wall 16 to thereby hold the walls 15 and 16 in substantially parallel position against the tension of the spring 18. The rear end of the rod 24 is provided with a handle portion 27 by 85 which the same is shifted to cause the finger 25 to engage and disengage the plate 16.

The device normally assumes the position shown in Fig. 2 when not in operation and when it is desired to lift the utensil 10, the projecting side wall 16 is passed upwardly 90 behind the bowed strap 11 as shown in Fig. 1, so that the strap lies between the walls 15 and 16, and in this position is engaged by the spring 18. The handle 12 is then 95 slightly moved upwardly to bring the side walls 15 and 16 into closer relation with the strap as shown in Fig. 4 so that by moving the handle 27 of the rod to the position shown in Figs. 1 and 3, the finger 25 is 100 caused to engage in the recesses 26 of the plate 16, to thereby hold the side walls 15 and 16 in locked parallel position. The bottom wall 17 constitutes a support for the lower edge of the strap 11 while the rod 24 105 prevents the lifter from being removed from the strap and in this position, the lifter is securely locked to the utensil and constitutes a secure handle therefor.

What I claim as new is:—
1. A utensil lifter including a handle portion, a U-shaped resilient lifting end formed

integral therewith, the lifting end including a pair of spaced side walls, there being an opening in the upper end of one of the side walls, a spring positioned between the side walls, the lower end of the spring being bent at an angle to limit the movement of the side walls toward each other, an eyelet carried by the upper end of said spring adapted to be positioned in said opening, a locking 5 rod rotatably carried by the handle projecting through said eyelet and slidably along the handle, and a finger carried by the end of said rod adapted to engage the free upper end of one of the walls.

15 2. A utensil lifter formed of sheet metal including a handle portion, a lifting portion, said lifting portion including a pair of side walls and an integral bottom wall of resilient metal normally forcing the upper 20 ends of the side walls outwardly, and a locking rod rotatably and slidably associated with the handle portion and having the end

thereof formed with a finger adapted to engage the upper end of one of the side walls to hold the side walls in substantial parallelism. 25

3. A utensil lifter including a handle portion, a lifting portion formed integral therewith and of substantially U-shape in side elevation, a compound curved spring positioned between the upright members of the lifting portion for normally holding the same separated, and a locking rod for the lifting portion rotatably and slidably carried by the handle and projecting beyond the handle portion and having at its end a finger adapted to engage the outer side wall of the lifting portion. 30 35

In testimony whereof I affix my signature in presence of two witnesses.

ANDREW SEKULA.
